UNITED STATES PATENT OFFICE.

HERMAN H. GARNER, OF POMONA, CALIFORNIA.

WET-FILTER AIR CLEANER.

1,426,177.

Specification of Letters Patent. Patented Aug. 15, 1922.

Application filed January 8, 1921. Serial No. 435,908.

To all whom it may concern:

Be it known that I, HERMAN H. GARNER, a citizen of the United States, residing at Pomona, county of Los Angeles, and State 5 of California, have invented a new and useful Improvement Comprising a Wet-Filter Air Cleaner, of which the following is a specification.

My invention relates to air cleaners which 10 are applied to the intake of internal combustion engines for the purpose of removing dust and dirt from the air before it enters the engine.

My invention is particularly applicable 15 to tractors or to automobiles which operate under extremely dusty conditions.

The principal object of my invention is to provide an air cleaner which will remove from the air before it passes to the 20 internal combustion engine practically any dust or dirt which may be carried therein.

Further objects and advantages will be made evident hereinafter.

Referring to the drawing which is for 25 illustrative purposes only,

Fig. 1 is a side elevation of a portion of the internal combustion engine to which my invention has been applied.

Fig. 2 is a cross section through the air 30 cleaner proper.

Fig. 3 is a section on a plane indicated by the line 3—3 of Fig. 2.

Fig. 4 is a section on a plane indicated by the line 4—4 of Fig. 2.

In the embodiment of my invention illustrated in these drawings, 11 is a cylindrical casing which is provided with a top 12 threaded at 13 to fit upon a pipe 14 which connects to the intake 15 of a carburetor 16 of an internal combustion engine 17. Inside the top of the casing 11 is a basket 20 formed of wire in which there is carried a body of fibrous material 21. The basket 20 is formed of wires which are bent up to 45 form a cone 22 in the top and a cone 23 in the bottom, so that the body of fibrous material has a conical depression at both its upper and its lower ends. The vertical wires 24 of the basket 20 are bent in as shown at 50 25 between two plates 26 which are crimped together at 28. Also secured between the plates 26 and 27 is a felt ring 29 which fits tightly inside the casing 11. The plates 26 and 27 have a central opening 30. Situated 55 directly below the plate 27 is an air inlet

pipe 31 which is so situated with relation to the casing 11 that it admits the air tangentially into that casing. Secured on the bottom of the casing 11 by means of hooks 35 which engage pins 36 is a can 37. The can 37 need not make an absolutely air tight joint with the casing 11.

The method of operation of the invention is as follows:

Before starting the engine, the can 37 is 65 removed and the basket 20 is pulled downwardly and out of the shell 11. The fiber 21 is then saturated by dipping in a bucket of waste oil and the basket is pushed back into the shell 11. A little oil is placed in 70 the can 37. The can 37 is then replaced. Whenever the engine is started, it creates a vacuum inside the upper portion of the shell 11, this vacuum drawing air in violently through the inlet 31. The incoming 75 air at atmospheric pressure carrying dust particles is caused by its direction of entrance to rotate inside the casing 11, forming a vortex. Due to the fact that the casing 11 is under a partial vacuum, the air 80 also expands upon entering the casing and in addition to the rotary motion indicated by the arrows A, there is a downward expansion in the outer layers of the vortex indicated by the arrows B so that the dust 85 particles are thrown violently outward and downward towards a body of oil 40, carried in the can 37. At first sight, it would appear that this downward movement of the dust particles is due to gravitation, but 90 I have found working with transparent wall containers that even if the casing 11 is turned upside down, the dust particles are still thrown violently into the direction of the arrow B or upward with the casing 11 95 upside down. These dust particles impinge upon the surface of the liquid 40 and are caught and retained thereby. The suction of the engine pulls clean air from the center of the vortex upwardly through the opening 30 and up inside the conical opening 23 in the bottom of the fibrous material 21. The air is then drawn through the fibrous material and through the pipe 14 into the intake of the carburetor.

By suitable proportioning of the parts, I am able to so construct my device that a portion of the oil 40 is sucked upwardly through the opening 30 into the pores of the fibrous material 21. This upward move- 113

ment of the oil 40 is due to the vortex, the pressure in the center of this vortex being considerably lower than at the edges. Working with transparent wall containers 5 I have found that the oil 40 forms an elevated point near the center of the can 37 the oil around the periphery of this can being depressed. This elevated point is higher as the speed of the engine is increased and 10 if the engine is run at a very high speed or the diameter of the case 11 is too small the whole contents of the can 37 may be sucked up into the fibrous material 21. In practice I find that far below this speed 15 drops of oil are whipped from the end of this point and drawn up into the fibrous material. In practice I prefer to make the diameter of the cleaner such that considerable amounts of oil are constantly being 20 drawn up into the fibrous material keeping it wet and washing the dirt caught therein back into the can 37 without making the diameter so small that a total evacuation of oil takes place even at high engine speeds. 25 The fibrous material 21 is preferably thoroughly saturated with oil before the engine is started and this saturation is maintained as described above. The oil caught in the fibrous material runs through the opening 30 and falls back into the can 37, carrying the dirt from the fibrous material with it. This dirt settles in the can 37 forming a sediment which can be readily removed by 35 detaching the can. In practice the oil 40 is utilized as a washing agent for the fibrous material 21, this washing taking place whenever the engine as described above is run.

The air passing upwardly through the opening 30 is freed of all the heavier dust 40 which is caught by the oil 40 but lighter particles are still carried by the air. The air passing through the opening 30 is still rotating violently and the dust therein tends to stratify, the heavier particles being carried in the outer layers of the rotating column of air, the center of this column being practically free from dust particles. As a consequence the dust is precipitated and caught on the outer edges of the cone 23, 45 the center and top of the cone remaining free from dust and unclogged thereby long after heavy dust deposits are built up on the lower and outer portion of the cone 23.

If the air entering the cone 23 were not 50 in rotation, the dust would be evenly deposited and the cone 23 would soon clog.

I claim as my invention:

1. An air filter comprising: a casing adapted to contain a body of liquid; a filter 55 in said casing above said body of liquid; and means for producing an air vortex in said casing of sufficient strength to draw said liquid into said filter.

2. An air filter comprising: a casing 60 adapted to contain a body of liquid; a filter

in said casing above said body of liquid; means for withdrawing air from said casing above said filter; and means for producing an air vortex in said casing of sufficient strength to draw said liquid into said filter. 70

3. An air filter comprising: a casing adapted to contain a body of liquid; a filter in said casing above said body of liquid; means for withdrawing air from said casing above said filter; and means for introducing air into said casing below said filter in such a manner as to produce an air vortex of sufficient strength to draw said liquid into said filter. 75

4. An air filter comprising: a casing 80 adapted to contain a body of liquid; a filter in said casing above said body of liquid; means for withdrawing air from said casing above said filter; and means for introducing air tangentially into said casing below said filter in such a manner as to produce an air vortex of sufficient strength to draw said liquid into said filter.

5. An air filter comprising: a casing; a cup adapted to hold liquid material and closing the bottom of said casing; an air filter formed of fibrous material and placed in said casing above said cup; means for introducing air tangentially into said casing between said filter and said cup in such a manner that a vortex is formed of sufficient strength to draw said liquid upwardly into said air filter; and means for connecting the upper portion of said casing above said filter with the intake of an internal combustion engine. 90

6. An air filter comprising: a casing; a cup adapted to hold liquid material and closing the bottom of said casing; means for detachably securing said cup to said casing; an air filter formed of fibrous material and placed in said casing above said cup; means for introducing air tangentially into said casing between said filter and said cup in such a manner that a vortex is formed of sufficient strength to draw said liquid upwardly into said air filter; and means for connecting the upper portion of said casing above said filter with the intake of an internal combustion engine. 100

7. An air filter comprising: a casing; a cup adapted to hold liquid material and closing the bottom of said casing; a removable air filter formed of fibrous material and placed in said casing above said cup; means for introducing air tangentially into said casing between said filter and said cup in such a manner that a vortex is formed of sufficient strength to draw said liquid upwardly into said air filter; and means for connecting the upper portion of said casing above said filter with the intake of an internal combustion engine. 115

8. An air filter comprising: a casing; a cup adapted to hold liquid material and closing the bottom of said casing; a removable air 120

filter formed of fibrous material and placed in said casing above said cup; means for introducing air tangentially into said casing between said filter and said cup in such a manner that a vortex is formed of sufficient strength to draw said liquid upwardly into said air filter; and means for connecting the upper portion of said casing above said filter with the intake of an internal combustion engine.

9. An air filter comprising: a casing; a cup adapted to hold liquid material and closing the bottom of said casing; an air filter formed of fibrous material and placed in said casing above said cup, said filter having a cavity extending centrally upward into the lower end of said fibrous material; means for introducing air tangentially into said casing between said filter and said cup in such a manner that a vortex is formed of sufficient strength to draw said liquid upwardly into said air filter; and means for connecting the upper portion of said casing

above said filter with the intake of an internal combustion engine.

10. An air filter comprising: a casing; a cup adapted to hold liquid material and closing the bottom of said casing; means for detachably securing said cup to said casing; an air filter formed of fibrous material and placed in said casing above said cup, said filter having a cavity extending centrally upward into the lower end of said fibrous material; means for introducing air tangentially into said casing between said filter and said cup in such a manner that a vortex is formed of sufficient strength to draw said liquid upwardly into said air filter; and means for connecting the upper portion of said casing above said filter with the intake of an internal combustion engine.

In testimony whereof, I have hereunto set my hand at Los Angeles, California, this 30th day of December, 1920.

HERMAN H. GARNER.
